Primary Examiner — John R Yeh*Assistant Examiner* — Dustin Andrew Griffith(74) Attorney, Agent, or Firm — Hemisphere Law, PLLC; Zhigang Ma(57) CLAIM

The ornamental design for a crossbody bag, as shown and described.

DESCRIPTION

FIG. 1 is a first perspective view of a crossbody bag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The dash-dash broken lines shown in the drawings depict portions of the crossbody bag that form no part of the claimed design. The dot-dash broken lines in FIGS. 1 and 9 illustrate the periphery of the enlarged views of the crossbody bag and form no part of the claimed design.

1 Claim, 9 Drawing Sheets(56)
